PHOTOGRAPHIC APPARATUS.

1,120,710.

Specification of Letters Patent. Patented Dec. 15, 1914.

Original application filed August 17, 1912, Serial No. 715,557. Divided and this application filed February 2, 1914. Serial No. 815,900.

To all whom it may concern:

Be it known that we, ELIAS GOLDENSKY and PERCY H. BARTLETT, citizens of the United States, residing in Philadelphia, county of Philadelphia, and State of Pennsylvania, have invented new and useful Improvements in Photographic Apparatus, of which the following is a specification.

Our invention relates to photographic apparatus and a system particularly adapted to studio photography, whereby the photographer is independent of daylight and depends upon artificial lighting of his subjects.

Our invention resides in a system involving sources of light whereby the subject to be photographed is first lighted by relatively low intensity sources and during the period of exposure of the sensitive plate or film these same sources emit light of greatly increased intensity. And in this connection our invention resides in means for simultaneously operating the camera shutter and increasing the voltage impressed upon the lamps, a plurality of which are normally connected in series with each other and then thrown into parallel with each other when exposure is made.

For an illustration of one of the forms our invention may take reference is to be had to the accompanying drawings, in which:

Figure 1 is a diagrammatic view illustrating a system for increasing the voltage impressed upon the electric lamps at the time exposure is made. Fig. 2 is a longitudinal sectional view through a bulb and contacting or switch apparatus. Fig. 3 is a longitudinal sectional view through a modified form of switching and shutter actuating apparatus.

Referring to Fig. 1, the lamps L are any suitable electric lamps, preferably such as will stand repeated subjection to voltage much higher than normal voltage, and for the purposes of this invention the lamps L may be incandescent electric lamps having tungsten, tantalum or other filament. Here the conductors 18 and 19 are the current supply conductors, and from them solenoid 28 is energized when bulb B is pressed to actuate the camera shutter S. The conductor 19 communicates through switch 22 with

the contacts 34 and 35 electrically connected to each other by a conductor 36. The contact 37 is connected to conductor 38 with 55 which one terminal of each of the lamps L is electrically connected. A contact 39 is connected to conductor 40 to which the other terminals of some of the lamps are connected, the other terminals of the remaining 60 lamps being connected to the conductor 18. The contact 41 is connected with conductor 40, and the contact 42 is connected through conductor 43 with conductor 18. The movable contact members 44 and 45 are insulated from each other by member 46 carrying the contacts 44 and 45 and pivoting them at 47. A spring 25 holds the members 44 and 45 normally in the position indicated in Fig. 1 and the pivoted link 26 connects 70 these members 44 and 45 with the core 27 of the solenoid. The lamps L in this case may be 55 volt lamps, pairs of which are connected in series with each other between conductors 18 and 40, the different pairs 75 being connected in parallel with each other between these conductors 18 and 40.

The operation is as follows: When the subject is in position, the switch 22 is closed, whereupon current will flow from conductor 18 through the pairs of 55 volt lamps in series to the conductor 40, through contact 39, member 44, contact 35, conductor 36, contact 34, to conductor 19, the difference in potential between conductor 18 and 19 being, for example, 110 volts. The lamps L burn therefore at their normal intensities because each lamp is then subjected to its normal potential difference, for example, 55 volts. When the bulb B is pressed, the 90 shutter S is actuated and the conductors 31 and 32 brought into electrical communication with each other by any suitable switching mechanism. The solenoid 28 is now energized and it attracts its core 27 toward 95 the left swinging the members 44 and 45 in a counter clockwise direction upon their pivot 47, causing contact 44 to leave contacts 35 and 39 and to engage contacts 34 and 37, contact 45 engaging contacts 41 and 42. Now current flows from conductor 18 through the upper set of lamps through conductor 38 to contact 37, through member 44 to contact 34, to conductor 19 with the

result that the upper set of lamps is subjected to 110 volts, or twice their normal voltage. Simultaneously however current flows from conductor 18 through conductor 48, contact 42, member 45, contact 41, conductor 40, through the lower set of lamps L to conductor 38, contact 37, contact 44, contact 34, to conductor 19, thus subjecting this set of lamps to double voltage also. In consequence all the lamps glow with extreme intensity. And when the exposure is terminated by release of the bulb B the solenoid is deenergized and the spring 25 restores the members 44 and 45 to the positions shown in Fig. 1, where the lamps glow at their normal intensities.

As an illustration of one form of means for simultaneously making the exposure and energizing the solenoid 28, reference may be had to Fig. 2 where B is the bulb communicating with the hollow member 48 to which the tube 49 is attached. Movable longitudinally of and around the tube 49 is the tube 50 having the opening 51 communicating with the tube 33 extending to the shutter. Registering with the opening 51 is the elongated opening 52 in the wall of the tube 49, longitudinal and rotary adjustment of the tube 50 upon the tube 49 maintains these openings 51 and 52 in register, but changes the position of the tube 51 longitudinally of the tube 49. Within the tube 49 is secured the member 53 having apertures 54 and carrying the screw 55 to which is connected a spring 56 whose other end is connected to the piston or plunger 57 to which is secured a stem 58, preferably of insulating material, carrying the bridging contact 59 adapted to bridge the contacts 60 and 61 supported on the insulating member 62 fixed within the tube 50. The conductors 31 and 32 connect with the terminals 60 and 61 respectively. When the bulb B is pressed air pressure is exerted through the apertures 54 and through the tube 33 upon the shutter mechanism and simultaneously upon the plunger 57 which then moves toward the right, as viewed in Fig. 3, causing the contact 59 to bridge the contacts 60 and 61, thereby causing the energization of solenoid 28. Upon release of the pressure on the bulb B terminating the exposure, the spring 56 retracts the plunger 57 and therefore separates the contact 59 from contacts 60 and 61, causing deenergization of the solenoid 28. By the longitudinal adjustment of the tube 50 upon the tube 49 the time of travel of the plunger 57 before contact 59 engages contacts 60 and 61 may be adjusted. And the plunger 57 may be so positioned that contact 59 has engaged or almost engaged contacts 60 and 61 before it uncovers the port or opening 52 to allow air to pass through the tube 33 to actuate the shutter.

In Fig. 2 a cylinder 63 communicates through aperture 64 with the tube 33 extending to the shutter. The plunger 57 is moved in this cylinder 63 by pressure upon the head 64 upon the rod 65 to which the plunger 57 is attached, finger grips 66 being provided upon the cylinder 63 so that the device may be actuated by one hand. The motion of the plunger 57 is opposed by the spring 67. Surrounding the rod 65 is the contact 68 adapted to bridge the contacts 60 and 61 supported by and insulated from the cylinder 63, the contacts 31 and 32, as before, connecting with the contacts 60 and 61 respectively. When the head 64 is pressed toward the right the plunger forces air ahead of it through the tube 33 to actuate the shutter. And contact 68 engages contacts 60 and 61 to close the circuit of the solenoid, the plunger 57 and rod 65 continuing their movement, if necessary, after the engagement of these contacts, through the member 68. When the pressure upon the head 64 is released the spring 67 retracts the plunger and finally pin 69 carried by the rod 65 engages the member 68 and carries it away from contacts 60 and 61, causing deenergization of the solenoid.

While Figs. 2 and 3 give examples of means for simultaneously operating the shutter and closing the solenoid circuit, it is to be understood that we are not limited to these constructions, except where it is specifically stated in the claims; and it is to be understood that the contacting mechanism may be situated at the shutter and moved by the shutter mechanism itself when actuated either by bulb or any other means.

This application is a division of our prior application Serial Number 715557 filed August 17, 1912.

What we claim is:

1. The combination with incandescent lamps normally connected in series with each other, means for energizing said lamps at predetermined voltage, switching mechanism for subjecting said lamps in parallel with each other to said predetermined voltage, a camera shutter, and means for simultaneously actuating said camera shutter and said switching means.

2. The combination with a source of current, a plurality of lamps normally connected in series with each other and said source of current, switching means for changing said lamps from series relation to parallel relation with each other with respect to said source, a camera shutter, and means for simultaneously actuating said switching means and said shutter.

3. The combination with a source of current, a plurality of lamps normally connected in series with each other and said source of current, switching means for changing said lamps from series relation to

parallel relation with each other with respect to said source, electro-magnetic means for operating said switching means, a camera shutter, and means for simultaneously operating said shutter and said electro-magnetic means.

In testimony whereof we have hereunto

affixed our signatures in the presence of the two subscribing witnesses.
